WINDOW WASHING AND CLEANING DEVICE

Gus J. Verhas, Jacksonville, Fla.

Application November 5, 1954, Serial No. 467,070

2 Claims. (Cl. 15—232)

This invention relates to window cleaning devices of the type having a pad on the end of an elongated telescoping handle to facilitate reaching the outside of glass panels of a window sash or in which a pair of pads are provided on the ends of elongated arms of a U-shaped handle whereby inner and outer surfaces of glass panels of window sash are cleaned simultaneously and wherein the necessity of reaching outside of the window is obviated.

The purpose of this invention is to eliminate the arduous task of cleaning outer surfaces of glass panels of window sash, particularly of the double hung type.

Various types of holders and other devices have been provided for washing and cleaning outer surfaces of glass panels of the sash of double hung and other windows; however, it is difficult to reach overlapping sections of the glass of double hung windows without sitting upon the window sill with the upper portion of the body on the outside or without operating the cleaning devices through comparatively narrow openings with arms of the operator extended through the openings. With this thought in mind, this invention contemplates an elongated telescoping or U-shaped bracket having window cleaning pads pivotally mounted at one end and a handle positioned on one side whereby the device may be conveniently held as it is operated for cleaning inner and outer surfaces of glass panels of window sash with the surfaces of the panels cleaned simultaneously.

The object of this invention is, therefore, to provide means for freely mounting window cleaning pads on the ends of arms of a U-shaped bracket whereby outer surfaces of glass panels of window sash may be readily cleaned from the inside of the window.

Another object of the invention is to provide a device for cleaning outer surfaces of glass panels of window sash in which the cleaning elements are readily removable and replaceable.

A further object of the invention is to provide a window cleaner having pads pivotally mounted at the end of an elongated handle in which the device is of a simple and economical construction.

With these and other objects and advantages in view, the invention embodies an elongated bracket formed with a pair of arms connected with an arcuate section providing a U-shaped structure with a handle on the bracket and with window cleaning pads pivotally mounted on extended ends of the arms.

Other features and advantages of the invention will appear from the following description, taken in connection with the drawings, wherein:

Figure 1 is a rear elevational view looking toward the back of a pad of a window cleaner of the type having a pad pivotally mounted on the end of a single telescoping arm.

Figure 2 is a cross section taken on line 2—2 of Figure 1 illustrating the construction of a window cleaning pad in which the parts are shown on an enlarged scale.

2

Figure 3 is a cross section taken on line 3—3 of Figure 1 with the parts shown on an enlarged scale illustrating the pointed cleaning pad gripping elements at the edges of the pad.

Figure 4 is an elevational view looking toward the back of the pad holder with the mounting arm and spring gripping element omitted.

Figure 5 is a cross section through the pad taken on line 5—5 of Figure 4 showing only the elements shown in Figure 4.

Figure 6 is a cross section through the telescoping arm of the pad holder or mounting bracket taken on line 6—6 of Figure 1 and showing a handle extended from the face of the bracket.

Figure 7 is a reduced elevational view of the spring gripping member that retains the cleaning material on the body of the pad.

Figure 8 is a side elevational view showing a window cleaner illustrating a pair of pads mounted on ends of telescoping arms of a U-shaped bracket.

Referring now to the drawing, wherein like reference characters denote corresponding parts, the improved window cleaner of this invention includes a pad, the body of which is formed with a plate 10 having rolled edges 11 and 12 at the ends and 13 and 14 at the sides with bearings 15 and 16 struck from openings 17 and 18 in the intermediate portion and with tabs 19 and 20 struck from openings 21 and 22, respectively, in the bearings, a spring gripping member 23 for clamping a sheet of material 24 to the face of the plate 10, and an elongated arm 25 pivotally mounted by a pin 26 in the bearings 15 and 16 and having a sheath 27 in which the arm is slidably mounted thereby providing a telescoping handle for the pad.

The sheath is also provided with a handle 28 which is secured, such as by welding tabs stamped on or bent from the ends, to the face thereof, as shown in Figures 1 and 6. The edges of the arm 25 and sheath 27 are rolled providing reinforcing beads 29. The end of the arm 25 opposite to that on which the sheath 27 is positioned is formed with a roll 30 through which the pin 26 extends and the pin is retained in position with a fastener 31.

The spring holding member 23 is provided with slots 32 and 33, that are positioned to receive the bearings 15 and 16 whereby with the member 23 pressed downwardly with the pin 26 removed and with the tabs 19 and 20 positioned in the openings 21 and 22, the central portion of the spring member is pressed to a position below the tabs 19 and 20 whereby the tabs are adapted to be bent outwardly, as shown in Figure 2, for retaining the spring member in gripping relation with edges of the sheet of material 24.

The spring member 23 is formed with webs 34 and 35 having notches 36 and 37, respectively, therein and, as illustrated in Figure 3, the notches are positioned to receive points 38 at one side and 39 at the other of the plate 10 whereby the spring member with the points 38 and 39 provides positive gripping means for retaining the sheet of material 24 on the body of the pad. The web 34 is connected to the central portion of the member 23 with arms 40 and 41 and the web 35 is connected to the opposite side with arms 42 and 43. The points 38 are struck from openings 44 on one side of the plate 10 and the points 39 are struck from similar openings 45 at the opposite side.

With the parts formed in this manner, a sheet of window cleaning material, such as indicated by the numeral 24, is secured against the face of the pad, or plate 10, with the edges secured by the arcuate webs 34 and 35 of the spring member 23 and with the pad pivotally mounted

by the pin 26 in the end of the arm 25 the pad is adapted to be worked over inner and outer surfaces of glass panels of window sash for cleaning the panels.

In the design illustrated in Figure 8, a pair of pads 46, such as pads formed on the body or plate 10, are pivotally mounted with pins 47 on the ends of arms 48 and 49 of a flexible elongated member 60 which is slidably mounted in sections 50 and 51 of a U-shaped bracket 52 and the bracket is provided with a U-shaped handle 53, similar to the handle 28. The member 60 is completed by having the lower ends of the arms 50 and 51 connected by an arcuate section 54 and the edges of the member 60 are rolled as indicated by the rolls 29 of the arm 25 and sheath 27.

By this means one of the pads 46 is positioned on the inside of a window sash and the opposite pad on the outside and with the arcuate section 54 extended through a comparatively thin slot at the lower end of the window the pads are adapted to be worked over inner and outer surfaces of glass panels of window sash whereby the sashes are readily cleaned without extending the arms or other parts of the body of the operator through the window.

With the cleaning pads mounted in this manner a pad may readily be inserted between the sash of a double hung window and also between the outer surface of the sash and a screen positioned on the window. It is, therefore, not necessary to take screens down when washing or cleaning windows.

The single arm cleaner, as illustrated particularly in Figure 1, is adapted to clean both the inside and outside surfaces of the glass, and with the cleaning pad held in this manner it may readily be actuated over the glass so that all parts thereof may be readily cleaned.

The cleaning sheet or material, as indicated by the number 24, may be chemically treated and may be removed and replaced, as desired.

It will be understood that modifications, within the scope of the appended claims, may be made in the design and arrangement of the parts without departing from the spirit of the invention.

What is claimed is:

1. In a window cleaner, the combination which comprises an elongated U-shaped bracket having a handle extended from one side and positioned at one end thereof, an elongated flexible member including a pair of arms telescopically mounted in said bracket and extending outwardly of said bracket, a pair of plates having rolled

edges with bearings extended from the intermediate part, a pin extended through each of the bearings on each of the plates and through the end of each of the arms for pivotally mounting a plate on each of the arms, a sheet of cleaning material positioned against the face of each of the plates with ends thereof extended around edges of each of the plates, and a spring member secured over the bearings extended from the back of each of the plates and positioned to frictionally engage the edges of the sheet of material extended around the edges of the plates for frictionally retaining the sheet of material in position on the plates, said plates having points extended rearwardly from edges thereof and said spring member having notches positioned to coat with said points for gripping said sheet of cleaning material on the face of each of the plates.

2. In a window cleaner, the combination which comprises a U-shaped bracket having an elongated telescoping member including a pair of arms slidably mounted therein, said arms extending outwardly of the bracket, a handle extended from one side of the bracket, plates having spaced bearings extended from rear surfaces thereof and positioned with ends of the arms of the member positioned between the bearings, pins extended through the bearings and through ends of the arms for pivotally mounting the plates on ends of the arms with the plates in abutting relation, layers of cleaning material positioned on opposed faces of the plates and extending around opposed edges of the plates, spring members secured over the bearings and positioned to frictionally grip edges of the sheets of cleaning material positioned over the plates, and gripping means at the ends of the plates and positioned to coat with notches of the spring member for retaining the sheets of cleaning material in position on the surfaces of the plates.
